WINDING DEVICE FOR LOOMS.

Application filed July 5, 1921. Serial No. 482,416.

This invention relates to weft replenishing looms, especially of the type wherein a filling carrier, such as an empty or almost empty bobbin, is ejected downward from the 5 shuttle by the pressure of a full filling carrier or bobbin when the yarn on the first one has almost run out or when the yarn breaks.

Such looms are generally provided with 10 feeler mechanism which, together with the replenishing mechanism, produces the result that each ejected bobbin has remaining upon it more or less yarn. To be used again the yarn must be removed from the bobbin. 15 This may be done by hand or by the use of bobbin stripping machines of which there are several types.

The free end of the yarn on the ejected bobbin has been cut or broken almost 20 variably before it has run out through the eye of the shuttle, and attempts have been made, with more or less success, to trap this end, to retard it, or to catch it in some way so that it can be automatically wound up and 25 thus unwound from the ejected bobbin before it goes into, or while it is in, the receiving can.

If this is done successfully, the use of bobbin stripping machines or bobbin strippers 30 is avoided, and each bobbin receiving can of the loom will contain several times as many bobbins cleared in this fashion as when dropped without being unwound. For this reason, the cans need to be emptied less frequently, which means less help.

To accomplish the desired results, it has heretofore been proposed to employ mechanism including a winding roll and guide, and also a brush with a winding roll, but in 40 the use of such mechanisms, the yarn jams between the roll and guide and it is difficult to remove it from the winding roll. When a smooth bobbin is employed, or where a spindle is used, as shown in my Patent No. 45 1,423,670, when the winding member is cleared it is necessary to catch new yarn around the smooth bobbin or spindle by hand in order to cause it to wind.

On the other hand, with a smooth bobbin, 50 such as shown in another patent, or where a spindle is used, as shown in application filed by me and pending herewith, when the winding member is cleared it is necessary to catch new yarn around the smooth bobbin

or spindle by hand in order to cause it to 55 wind. This causes delay and is rather a troublesome operation for the reason that in order to be readily stripped, the bobbin or spindle should be smooth, and this very smoothness tends to permit the yarn to slip 60 until the smooth surface is covered by enough yarn to catch the yarn from each bobbin thereafter ejected from the spindle.

My present device includes a rapidly revolving spindle, instead of a bobbin, on 65 which the yarn is to be wound provided with a finger longitudinally positioned from one end, preferably not the free end, and preferably made in the form of a spring catch. This spindle is preferably located 70 behind the path of the bobbin as it is ejected from the shuttle, and preferably is associated with trapping means in the lay beam which will positively grasp the end of the 75 yarn left in the shuttle eye after the bobbin is ejected, and will hold it long enough to be caught by the finger and wound on the spindle.

By using such a finger, especially in connection with a tapered spindle, I utilize the 80 well known tendency of a belt to crawl along a conical pulley to the large end, and also utilize the fact that the shuttle eye when the bobbin is ejected is in its farthest position 85 from the warp, and that when the shuttle is picked and moves towards the warp, thus tending to clear itself from the tail of yarn from each ejected bobbin, it also tends to carry that tail toward the warp. With a trap in the lay beam or other similar device 90 which opens at each pick, gravity causes the yarn to swing toward the warp at the second pick. I therefore prefer to locate my finger catch at the large end of a tapered spindle, 95 such large end being nearest the loom frame and warp whereby both tendencies are utilized.

The spindle may be tapered and the finger parallel with its axis, or they may be arranged in any way whereby there is a short 100 distance or mouth between the free end of the finger, or of each finger, and the spindle, large enough for the yarn to enter, and facing in the direction from which the yarns tends to move.

In the drawings, Fig. 1 is a front elevation showing part of the breast beam and lay beam of a magazine loom with my pre-

ferred form of device in position, parts being broken away to show the construction.

Fig. 2 is an elevation from the left of Fig. 1, with parts broken away and showing 5 two positions of the lay beam.

Fig. 3 is a front elevation showing part of the lay beam and winding member of a slightly different form from Fig. 1, and a retarding member in place of a trap.

10 Fig. 4 is a front elevation enlarged, showing my preferred form of winding member as illustrated in Fig. 1.

Fig. 5 is a detail in elevation showing a modified form of winding member.

15 Fig. 6 is a front elevation in detail showing another form of winding member, and Figs. 7 and 8 are detail elevations showing still other forms of winding members.

In the drawings, A represents the breast 20 beam, L the lay, 10 a part of the frame, C the picker and 12 the magazine of a magazine loom of the Crompton & Knowles type. 9 represents a full bobbin in the magazine, 8 a full bobbin which has just been delivered 25 into a shuttle, and B the bobbin from which the yarn 13 has almost been exhausted and which has been discharged from the shuttle, such as D, having an eye 19.

20 represents the end of the tail of yarn 30 13 from the discharged bobbin B which, at the time indicated, still runs through shuttle eye 19 and out toward the warp along the lay beam.

Referring to Fig. 2, 21 and 22 represent 35 the opposite walls of the passage 11 indicated in Fig. 1 in the lay beam L, through which the empty or almost empty bobbin, such as B, is discharged from shuttle D. 6 is a sloping apron which directs the shuttle 40 into the can K.

In my preferred construction, I use a trap, indicated by T in Figs. 1 and 2, located preferably on the lay beam in position to catch the loose end of the yarn on the ejected bobbin and to hold it until said yarn is caught by the catch on my winding spindle or member and begins to be wound up thereby.

As shown, this trap comprises a spindle 30 carried in bearings 23 and 24 shown as 50 attached to the outside of the lay beam on the side 22. The arms 31 and 32 extend at right angles to spindle 30, preferably so curving that the cross bar 33 which connects them will rest snugly up against the top 55 part of the side 22 when the trap is closed. Between this bearing and the side 22 is thus formed what I may call a trap bobbin passage.

The returning spring 35 is attached at one 60 end to spindle 30 and at the other end to bearing 23, and is so positioned that it tends to fold up the trap against the side 22 when not pushed open by the dagger 36. This dagger 36 is connected at 37 to any station- 65 ary part of the frame 10 and passes through

a suitable hole 27 in the side 22 of the lay beam. The dagger and hole are so positioned that the dagger will strike 31 when the lay beam has almost come up to the nearest point to the breast beam and immediately before the empty bobbin is discharged. The dagger 36 may be rigid or may be a metal rod which can readily be bent so as to adjust the parts correctly.

70 Preferably, the dagger strikes at a point 75 on the trap arm pretty well down toward the spindle so that the cross bar 33 will move rapidly over to the side 21 and allow the bobbin to be ejected between it and side 22 through the trap bobbin passage. The trap is thus opened as the bobbin B is discharged, but is closed instantly thereafter by the spring 35 as the lay beam recedes in time to catch and hold the loose end of the yarn before it is carried past by the descending bobbin. The trap bar 33 might be rough, or the side 22 might be rough, whereby the yarn might be held in one position, or it may preferably be smooth whereby, before or at the second pick when 90 the trap is again opened, the yarn 13 slips over to the left to the position shown by the dotted lines in Fig. 1.

95 As soon as the tail end is caught, the bobbin being still in flight will be spun around, unwinding to a certain extent as it drops into the can.

With this device I locate behind the path 100 of the bobbin as it is ejected from the shuttle, as clearly shown by the dotted lines in Fig. 2, a spindle S revolvable in bearings 14 attached to frame 10 which carries a whirl 16 which is rapidly revolvable by a belt 17, as clearly shown in Fig. 4.

105 Preferably, this spindle S tapers down from its large end 41 near the whirl to a small end 40, and preferably the whirl is protected at the top by a guard 46 and at the bottom by a guard 47 so that the yarn cannot become entangled therewith. As 110 shown in Figs. 1 and 4, I prefer to provide a short spring catch 42 fixed to the large end 41 and having its free end 43 slightly turned outward, and the long latch 44 fixed at the end 41 having its free end 45 turned 115 outward, both being positioned substantially longitudinally from the large end of the spindle.

120 With this tapered construction, as shown in Fig. 2, as the lay beam L moves back and forth toward the breast beam and the trap opens and closes, the tail of the yarn 13 between the shuttle S and trap T is loosened and tightened, and for this reason crawls from the small end 40 of the spindle toward the large end 41 until it is caught by one of the spring catch fingers 42 or 44, when it immediately becomes entangled and is rapidly wound up. If one spring finger does not catch it, the other will, and as it winds 125 130

these are pressed in toward the spindle. With this construction, after sufficient yarn has been wound, as indicated by the dotted lines in Fig. 4, it can be readily stripped off 5 toward the small end of the spindle, the taper of the spindle permitting this to be easily done.

While I prefer to use a positive action trap, I may, as shown in Fig. 3, use a clearer 10 for retarding the tail of the yarn, such as shown in patent to Moore, bobbin stripper for weft replenishing looms, dated June 16, 1908, No. 890,865. In Fig. 3, the trap is omitted and the spindle S is shown as having one spring catch 82 instead of two, and 15 5 represents a rough piece of cloth or card clothing intended to retard or catch the tail end 20 of the yarn 13 from bobbin B. As the yarn floats or is carried over from the 20 dotted position to the full position shown at 3 and strikes the clearer 5, it assists in retarding the end until it is caught by the winding member S.

I find, however, that my peculiar form of 25 winding member will work without the trap if the clearer cloth 5 is entirely omitted or fails to function.

Various modifications of my winding member may be used with more or less success, such as those shown in Figs. 5, 6, 7 and 8.

In Fig. 5, S represents a tapered spindle revoluble by a whirl 16 having at the large end a disc 50 from which projects a rigid 35 finger 51 positioned longitudinally from that end of the spindle.

In Fig. 6, the shaft 60 carries driving whirl 61, a protecting disc 62 and thimble 63, in which is a tapered hole 64 to receive the 40 small tapered end 65 of a winding member P which, preferably, is of metal and has bent around from the large free end 66 a rigid finger 67 longitudinally positioned from the large end thereof. When sufficient 45 yarn is wound upon this device, it can be pulled out from the hole 64, stripped from the end 65, and replaced.

In Fig. 7, the shaft 70 forms part of spindle 72 of uniform diameter throughout, revoluble by a whirl 71. At the free end 77 is a catch 75 having an enlarged portion with a hole 73 which allows it to be slipped over the end 77 and held in place by a set screw 74. This member has a catch finger 76 which 55 extends substantially horizontally from the free end, preferably at a slight angle so as to tend to throw the yarn down toward the middle of the spindle. To strip this device, member 75 is removed and the yarn stripped 60 by hand.

In Fig. 8, the spindle S, whirl 16 and guard 46 will be the same as shown in Fig. 4, except that there are no spring fingers on the spindle. In place thereof a wooden 65 bobbin H having a spring finger 79 attached

at one end is forced on the spindle and revolves as part thereof until filled with yarn, when it can be removed and stripped and replaced by another.

It is obvious that instead of one or two 70 fingers more might be used, and that these might be shorter or longer and either rigid or elastic. I find, however, that two, such as shown in Figs. 1 and 4, either with or without the ends bent outwardly, are generally 75 effective.

Broadly speaking, I claim the combination of a positive trap as distinguished from a retarding device for the severed end of the 80 yarn, with a positive action device for starting the winding of the yarn on a new, clean spindle or bobbin, as distinguished from a friction device or other non-positive device.

More specifically, I claim a finger extending longitudinally of the spindle or bobbin 85 in such manner that it forms an open mouth between it and the surface of the spindle or bobbin and narrows down in a V shape so that yarn entering will wedge therein.

Still more specifically, I claim a spring or 90 elastic finger as being entirely new.

I claim:

1. The combination with a weft replenishing loom, of a revolving spindle which tapers down to its end having a spring catch 95 extending lengthwise thereof which is turned up at the end, said spindle being located behind the path of the bobbin as it is ejected from the shuttle, and a trap located in position to positively catch the loose end of the 100 yarn on the ejected bobbin and to positively hold it until said yarn is caught by the catch on the spindle and begins to be wound up by the spindle.

2. The combination with a weft replenishing loom, of a horizontal rapidly revolving spindle which tapers down to its end having a finger extending from the large end lengthwise thereof, said spindle being located behind the path of the bobbin as it is ejected 110 from the shuttle, and a trap located in position to positively catch the loose end of the yarn on the ejected bobbin and to positively hold it until said yarn is caught by the catch on the spindle and begins to be wound up 115 by the spindle.

3. A tapering winding spindle provided with a catch consisting of a spring strip secured at one end to the larger end of the spindle and extending a substantial distance 120 longitudinally thereof alongside the spindle in spaced relation therewith and being turned up at its free end.

4. A tapering winding spindle provided with a catch consisting of a spring strip secured at one end to the larger end of the spindle and extending a substantial distance 125 longitudinally along side the spindle in spaced relation therewith.

5. The combination with a weft replenish-

- ing loom, of a revolving spindle which tapers down to its end having a spring catch extending lengthwise thereof which is turned up at the end, such spindle being located behind the path of the bobbin as it is ejected from the shuttle, a driving whirl on said spindle, a guard for said whirl, and a trap located in position to positively grip the loose end of the yarn on the ejected bobbin and to hold it until said yarn is caught by the catch on the spindle and begins to be wound up by the spindle.
6. The combination with a weft replenishing loom, of a revolving spindle which tapers down to its small end having a spring catch extending from its large end lengthwise forming a V with the surface thereof, said spindle being located behind the path of the bobbin as it is ejected from the shuttle, and a trap located in position to positively grip the loose end of the yarn on the ejected bobbin and to hold it until said yarn is caught by the catch on the spindle and begins to be wound up by the spindle.
7. In a bobbin clearing attachment for weft replenishing looms, a revoluble waste winding member provided with a finger longitudinally positioned from one end and extending lengthwise forming a V with the surface thereof.
8. In a bobbin clearing attachment for weft replenishing looms, a revoluble waste winding member provided with a spring finger longitudinally positioned from one end combined with a holding member proximate the shuttle to catch the tail of the yarn.
9. In a bobbin clearing attachment for weft replenishing looms, a revoluble waste winding member provided with a plurality of spring fingers longitudinally positioned from one end.
10. The combination with a weft replenishing loom, of a revolving spindle having a finger extending lengthwise thereof with its free end a short distance from the spindle said spindle being located behind the path of the bobbin as it is ejected from the shuttle, and a trap located in position to catch the loose end of the yarn on the ejected bobbin at each pick and to positively grip it and release it intermittently until said yarn is caught by the finger on the spindle and said loose end is wound up thereon.
11. The combination in a weft replenishing loom, of a revolving winding member which has a finger extending longitudinally thereof with its free end a short distance therefrom, said winding member being located behind the path of the bobbin as it is ejected from the shuttle, and a trap located in position and adapted to positively grip the loose end of the yarn on the ejected bobbin and to release it and grip it at each pick thereafter until said yarn is caught by said winding member and said loose end is wound up thereon.
12. A winding member provided with a finger longitudinally positioned from one end having its free end a short distance from the body of said winding member and extending down to its other end so as to form a V with the surface thereof.
13. In a bobbin clearing attachment for weft replenishing looms, a revoluble waste winding member provided with a spring finger longitudinally positioned from one end having its free end a short distance from the body of the waste winding member.
14. In a bobbin clearing attachment for weft replenishing looms, a revoluble waste winding member provided with a finger longitudinally positioned from one end having its free end a short distance from the body of said winding member, combined with a holding member proximate the shuttle to catch the loose end of the yarn and to positively grip it and release it at each pick thereafter.

JAMES T. MALLOY.
